UNITED STATES PATENT OFFICE.

JOHN R. FREEMAN, OF PROVIDENCE, RHODE ISLAND.

PORTABLE WINCH.

1,270,809.

Specification of Letters Patent.

Patented July 2, 1918.

Application filed May 21, 1915. Serial No. 29,639.

To all whom it may concern:

Be it known that I, JOHN R. FREEMAN, a citizen of the United States, and resident of Providence, county of Providence, State of Rhode Island, have invented an Improvement in Portable Winches, of which the following description, in connection with the accompanying drawing, is a specification, like characters on the drawing representing like parts.

This invention relates to improvements in winches and the purpose thereof is to provide a portable winch operable by a system of differential mechanism preferably in the form of planetary gearing by means of which a powerful pull can be exerted upon a flexible member such as a rope of wire, hemp or other material, which is secured to, and adapted to be wound upon the drum of the winch when the frame of the apparatus is suitably anchored and the winding mechanism actuated.

An apparatus of this character is particularly desirable under many circumstances, for example it is frequently desirable to carry a portable winch of this character in an automobile so that it may be readily used to pull the machine out of a position of distress. Another instance is as a support for a scaffold or platform such as used by painters, in which the winch may be used to raise and lower the platform along the side of the building.

Such winches may also be employed advantageously in any industry where it is necessary to raise and lower or move heavy objects by hand power, and particularly where a compact apparatus having a long reach or scope is desired.

The preferred embodiments of the invention disclosed herein comprise a frame having a rotary driven member, preferably a drum rotatably mounted therein upon which a coil of rope, wire, or other flexible material may be reeled, the drum being rotated preferably by means of a train of planetary differential gearing which may be actuated by a crank, ratchet lever or other means.

One of the objects of the invention is to provide an apparatus of the character above described which is capable of transforming the power applied to a hand operated crank, or the like, into a powerful pull upon the rope, so that by a relatively small exertion

the operator may displace, or lift, a very heavy weight.

Another object of the invention is to provide an apparatus of the character described which may operate under different speeds of revolution of its crank so as to give either a slow and very powerful pull upon the rope, as above indicated, or a more rapid pulling motion thereupon with correspondingly less power according to the position in which the actuating crank is attached to the drum operating mechanism.

Another object of the invention is to provide, in an apparatus of the character referred to, means for releasing the drum from its actuating mechanism in such a manner that the drum may be permitted to rotate freely for the purpose of reeling off the rope rapidly; or in which the rope may be wound upon the drum by power applied directly to the rim thereof, while the usual drum actuating mechanism remains stationary.

Other objects of the invention will more fully appear from the following description and the accompanying drawings and will be particularly pointed out in the annexed claims.

The drawings illustrate certain preferred embodiments of the invention, but it will be readily understood that the invention may be embodied in other forms within the meaning and scope of the subjoined claims.

In the drawings:

Figure 1 is a plan view of one form of winch embodying my invention.

Fig. 2 is a vertical axial sectional view of the same.

Fig. 3 is a sectional view on lines 3—3

Fig. 2 partly broken away to disclose the relation of the differential gearing,

Fig. 4 is a detail sectional view of a portion of the winding drum,

Fig. 5 is a detail view of a crank plate or disk through which power may be imparted to the planetary gears,

Fig. 6 is a detail view in perspective of one set of the planetary gears, comprising gears of different pitch which engage respectively annular racks upon the frame and an internal gear upon the drum, for the purpose of imparting through the planetary gearing a differential rotation to the winding drum,

Fig. 7 is a side view of a modified form of winch embodying my invention showing the gears of the system mounted upon anti-friction rollers,

5 Fig. 8 is a longitudinal vertical sectional view of the same,

Fig. 9 is a vertical sectional view of a modified form of winch in which a single planetary member is employed,

10 Fig. 10 is a vertical axial sectional view of the same, and,

Fig. 11 is a detail side view peripherally broken away showing particularly the means for detachably connecting the drum to its 15 actuating mechanism.

The preferred form of winch illustrated in the accompanying drawings comprises a frame composed preferably of two substantially triangular metal plates 1-2 spaced 20 apart at their apexes by suitable posts 3, which may be integral with one of said members and connected together by screws 4 passing through said post and screw threaded into the frame at one side as illustrated in Fig. 3.

It will however be understood that the frame may be constructed in any other suitable manner.

30 A clamp may be secured to one of the posts 3 for the purpose of receiving the end of an anchor rope. As illustrated herein the clamp comprises a plate 5 having yoke members 6 embracing the post 3 and a central stud 7 surrounded by a groove adapted 35 to receive the bight of a rope 8; the rope being clamped firmly within said groove by a cover plate 9 (see Fig. 1).

A handle 10 in the form of a yoke may be secured to another of the posts 3 while 40 the third of the posts may be conveniently utilized to support a pawl, adapted to engage suitable ratchet teeth upon the winding drum to prevent the backward rotation thereof. The side frames 1 and 2 are provided with circular apertures adapted to receive the planetary gearing, the walls 11 and 45 12 of said apertures being adapted to form bearings for the planetary gears, hereinafter to be described. The side frames are preferably provided with inwardly extending annular flanges 13 having radial teeth 14 forming gears surrounding the apertures aforesaid adapted to be engaged by certain of the gears of the planetary system, and acting as a series of fulcrums for said planetary gear.

50 In the construction herein shown the differential planetary gear which engages the offset is shown as comprising two outer gears engaging the gears on the frame, with an intermediate drum actuating gear, for the purpose of more evenly distributing the strains within the apparatus and for the purpose of relieving unbalanced strains, it will be obvious that if either of the outer 55 gears were omitted the apparatus would

still perform its function, although less efficiently.

Annular recesses 16 surrounding the apertures serve to receive cover plates 17, 18, secured by screws 19 to the side frames to retain the rotating planetary gears in operative relation within the frame. The gearing, as illustrated in Figs. 1 to 6 inclusive, comprises a central sun gear or actuator 20 comprising a hub portion 21 and an outwardly 75 extending end 22 which preferably may be hexagonal in form, as illustrated in Fig. 1, to enter a corresponding recess in the end 23 of an actuating crank 24 of any suitable length and provided with a hand grip 25. 80 The crank 24 may be provided with an additional engaging member 26 preferably in the form of a cross adapted to engage annular projections 27 upon a crank plate or disk 28 provided with apertures 29 adapted to form 85 bearings for the ends of the series of planetary gears which will hereinafter be described. The projecting end 22 of the actuator may be provided with recesses or holes adapted to receive a locking pin 30 and the 90 annular projections 27 may be provided with like apertures adapted to receive a pin 31 upon said crank, the pins 30 and 31 being normally pressed inwardly by a spring 32 which may be fixed to said crank by suitable 95 screws 33.

The actuator 20 is provided with a series of gear teeth 34 adjacent to one end, and at the other end is provided with a similar gear 35, which in order to permit the assembling of the parts of the apparatus, may be detachably secured upon an extension or stud 36 preferably of angular cross section, to prevent relative rotation between the gear 35 and the gear 34, the gear 35 being secured upon said stud by a nut 37 or in any other suitable manner.

By reason of the fact that the drum when actuated is adapted to exert a very powerful pull, of several tons, upon the rope it is 110 necessary to eliminate so far as possible the friction between the relatively rotating parts. In order to accomplish this function I have provided each of the members with cylindrical annular bearing surfaces adapted to engage like bearing surfaces upon the other members in rolling contact, the diameters of said cylindrical surfaces being preferably the same as the pitch diameter of the adjacent gears, and have also provided bearing surfaces upon the frame adapted to be engaged in rolling contact by the bearing members upon the elements of the planetary system.

115 A preferred embodiment of this construction is shown in Figs. 1, 2, and 3 of the accompanying drawings which eliminates very largely the friction between the relatively rotating members and at the same time presents an exceedingly rigid construction for 120 125 130

maintaining the gears in the most efficient contact.

The actuator at its ends may be provided with rings 38—39 which may be integral with the actuator or may be made separately therefrom and shrunk thereupon, these rings being adapted to engage similar rings on the series of planetary gears which revolve around the central actuator. As 10 illustrated in Figs. 1 to 6 of the drawing the actuator is provided with eight teeth at each end spaced apart in such a manner as to leave an annular space 40 therebetween in which the central gears of the traveling 15 or planetary gears may pass without interference. The planetary gears desirably are of a composite character of the form illustrated in Fig. 6 and may comprise three gears rigidly secured together upon a central shaft or preferably cast integral throughout, the outer gears 41—42 each having the same number of gear teeth and the intermediate gear 43 a different number of teeth and a different pitch. These members 20 may, as stated, be cast integral in the form of a hollow toothed cylinder, a suitable bearing hub 44 being secured in the end of the cylinder and provided with a cylindrical axis 45 seated in the circular apertures 25 29 of the crank plate 28. The hub 44 and the cylindrical axis 45 desirably are made to fit loosely but non-rotatably within the hollow toothed cylinder to permit the planetary 30 gears to float freely and thus automatically 35 to adjust themselves in such a manner that each takes its proportionate share of the stress.

By spacing apart the members of the planetary gears which engage fixed annular 40 gears upon opposite sides of the casing and by placing the gear which engages the annular gear of the drum between them the stress imposed upon the mechanism becomes balanced and the tendency to end-crawl is 45 eliminated.

The ends of the planetary gears desirably are provided with bearing rings 46—47 which may engage the corresponding bearing rings 38—39 of the actuator, thus providing 50 a rigid construction adapted to withstand lateral strains especially since the rings 46—47 also engage the annular bearing surface 11—12 of the frame. It will be understood that the bearing rings upon 55 the central actuator and upon the planetary gears should be of precisely the pitch diameter of the respective gears in order to permit proper relative rotation of the gear system, and in order that these bearing rings 60 may take the place of ordinary shaft bearings and become in effect roller bearings.

The central gear 43 desirably is spaced apart from the gears 41—42 to receive a ring 50 provided with an internal gear 51 adapted 65 to mesh with the central teeth 43 of the

planetary gears, the ring 50 supporting and being preferably detachably connected to the winding drum 52.

If rotation is imparted to the actuator 20 through the crank 24, the gears upon said 70 actuator which engage the teeth upon the planetary gears will transmit rotary motion to them and since the planetary gears also engage the internally toothed gears 14 of the main frame the rotation of the actuator 75 will cause the planetary gears to travel in a circular path.

It will be obvious that by reason of the fact that the central gear 43 is of a different pitch than the gears 41 and 42 a differential 80 movement will be imparted to the ring 50 and the drum 52.

If the central portion 26 of the crank 24 is engaged with the annular projections 27 of the crank plate 28 in which the planetary 85 gears are journaled, power will be applied directly to the planetary system so that a greater speed of rotation will be imparted to the drum, the central actuator or sun wheel 20 revolving idly during such operation.

It will thus be obvious that rotary motion may be transmitted from the crank to the drum either through the central sun wheel, to provide for a slow movement of the drum 95 with the transmission of a great amount of power; or may be applied directly to the planetary gears to attain a greater speed of rotation of the drum, with a corresponding decrease in power as may be useful in 100 hauling in the slack rope.

It is desirable that the winding drum shall be rotatable independently of the actuating gearing in order to provide for the rapid unreeling of the rope or wire which 105 is coiled upon the drum, and also to permit the rope to be rapidly reeled up after the device has been used.

Provision is made for the independent rotation of the drum in the device illustrated in Figs. 1 to 6 of the drawing by forming the ring 50 with a series of inclined notches 55 to form ratchet teeth 56 adapted to be engaged by a pawl 57 which may conveniently be carried in a recess 58 in the body of the drum 52, this pawl being secured therein by a cover plate 59 suitably attached to the end of the drum. The pawl may be of the form illustrated in Figs. 3 and 4 which comprises the ratchet engaging member or pawl 57 having a cylindrical stud seated in a corresponding socket at the end of the recess 58 and provided with a laterally extending arm 60 lying within the plane of one of the outer flanges 62 of the 110 drum. The arm 60 may be maintained in interlocked position as illustrated in Fig. 3 by a dog 63 having a projection 64 at its end engaging the arm 60, or it may be retained out of engagement with the ratchet 115 120 125 130

by a similar dog 65 having an offset end 66 adapted to engage the other side of the pawl arm 60.

When the pawl 57 is in engagement with 5 a tooth 56 of the ring 50 the drum will rotate in unison with the ring, but if the pawl is disengaged from the ring in the manner aforesaid the drum may be rotated freely independently of the gearing, which 10 will remain stationary.

The relative positions of the ring 50 and the drum 52, during the free rotation of the latter, may be preserved by providing guiding means upon one of the members engaging 15 a recess in the other. As illustrated herein, the means provided comprises an annular groove 67 in the outer periphery of the ring 50 which is engaged by a screw 68 seated in the drum 52 and extending into 20 said annular groove.

In order to prevent the backward rotation 25 of the drum, by a heavy weight sustained if the hand is temporarily removed from the crank when the rope is being coiled upon the same, one or both of the flanges 62 may be provided with notches forming ratchet teeth 70 adapted to be engaged by a pawl 71 pivotally mounted upon one of the posts 3 which separate the sides of the frame, as 30 heretofore described.

The pawl 71 may be normally retained in engagement with the teeth 70 by a spring 72 anchored in the post 3 and bearing upon the pawl 71 in the usual manner. In order 35 to lock the pawl out of engagement with the teeth 70 of the drum during the unreeling of the rope the pawl 71 may be provided with a tail 73 having an angular end adapted to enter an undercut recess in a dog 74 pivotally mounted upon a stud 75 upon the side 40 of the frame.

In order to unreel the rope it is merely necessary to disengage the pawl 71 from the ratchet teeth 70 and to lock it out of engagement therewith. When the rope has been 45 sufficiently unreeled the anchor rope 8 may be attached to a stationary object and the usual hook 76 upon the end of the rope 77 which encircles the winding drum attached 50 to the object to be moved. Power may then be applied by the handle, either through the actuator 20 in which case the rotation of the actuator will cause the rotation and revolution of the planetary gears 44-45 and 55 because of the difference in pitch between the gears 41-42 and 43 will cause through the internal annular gear 51 the slow rotation of the ring 50 and the attached drum 52, thus winding the rope upon the winch 60 and exerting a powerful pull thereupon.

If an object of less weight is to be moved which does not require the power produced in the manner aforesaid or if slack rope is to be reeled in the central recess 26 of the 65 crank handle may be applied to the annular

projection 27 of the disk 28, in which the planetary gears are journaled, and rotation imparted directly to the planetary system, permitting the central actuator to run idly. This movement of the planetary gears will 70 transmit a differential movement to the ring but at a much increased speed over that which is imparted through the rotation of the actuator above described so that light objects can be moved with much greater 75 rapidity than very heavy objects.

In the apparatus illustrated in Figs. 1 to 6 the actuator is provided with eight teeth as are also the outer gears of the planetary system. The fixed annular racks 80 are provided with twenty four teeth which are engaged by the outer teeth of the planetary gears aforesaid. The inner gear 43 is provided with seven teeth and the movable internal ring 50 of the drum with twenty 85 three teeth. In this construction each rotation of the drum requires about forty six revolutions of the crank when the same is rotated through the central actuator, or eleven and five tenths rotations when the 90 crank engages the crank disk 28, so that it will be apparent that when the planetary gearing is actuated through the crank plate 28 it will be rotated at approximately four 95 times the rapidity with which it is actuated through the central actuator or sun wheel 20.

When it is desirable to reel up the rope after the device has been used the pawl 57 may be disengaged from the ring 50 in the manner aforesaid and the drum rotated by 100 hand at a greater rapidity than could be accomplished through the planetary gearing.

A modified form of my invention, illustrated in Figs. 7 and 8, comprises a frame consisting of circular plates 80-81 having 105 diametrically opposite extensions 82-83 each of which may be provided with hollow oppositely extending spacing posts 84, complementary extensions 82-83 being secured together by suitable screws 85 seated in one 110 set of posts and screw threaded into the other as shown in Fig. 8.

The central portions of the circular plates 80, 81 desirably may be provided with inwardly projecting flanges 86, 87 surrounding central apertures 88-89 and adapted to form recesses for bearing rollers 90, said rollers engaging respectively the hub 91 of an actuator and the hub 92 of a spider 93 forming with an oppositely disposed disk 94 115 a frame for rotatably supporting a series of planetary gears 95.

As illustrated in Fig. 8 of the drawing the actuator is provided with a gear 96 adapted to intermesh with similar gears 97 upon the planetary series and the hub of the actuator is provided with an extension 98 projecting beyond the outer face of the winch frame and desirably is of rectangular or hexagonal form to receive a similarly 130

apertured end of a crank. The hub of the actuator is apertured near its end to receive a cylindrical extension 99 extending from the hub 92 of the spider 93. A series of 5 anti-friction rollers 100 desirably surround the extension 99 so that the hub 98 of the actuator will rotate easily thereupon.

The planetary gears 95 desirably may be mounted upon shafts 101 which are supported at their ends respectively in the spider 93 and the circular plate 94, a series of anti-friction rolls 102 being desirably interposed between said shafts and the hubs of the planetary gears 95. The teeth 97 of 15 the planetary gears engage the teeth of an annular rack 103 formed upon a flange 104 projecting inwardly from the side plate 80, the opposite end of the planetary gear being provided with a series of teeth 105 of different pitch which engage an annular series 20 of gear teeth 106 projecting inwardly and preferably integral with the drum 107. The drum 107 may be provided with the usual flanges 108—109 which may be provided 25 with apertures 110 to reduce the amount of metal and consequently the weight of the device. In order to maintain the drum 107 in proper position within the frame the drum may be provided centrally with a pair 30 of adjacent ribs 111 and 112 forming therebetween an annular recess 113, and each of the planetary gears may be provided with a projecting rib 114 engaging the annular recess 113 so that the drum will be maintained 35 at all times in proper position within the supporting frame. By making these cylindrical surfaces of the pitch diameter of the adjacent gear these ribs of the planetary system serve as roller bearings for the 40 drum.

In order to prevent backward rotation of the drum one of the flanges 109 may be provided with a series of ratchet teeth 115 adapted to be engaged by a spring pressed 45 pawl 116 pivotally mounted upon a stud 117 extending inwardly from the extension 83 of the supporting frame. Suitable yokes 118 and 119 may be pivotally attached to the posts 84 which separate the side frame and the anchoring rope may be attached to either 50 one or the other of said yokes.

In the operation of the device the yoke 118 will be attached to the anchoring rope and the rope from the drum 107 will be attached to the object to be moved. Power 55 may then be applied either through the hub 98 of the actuator or through the hub 92 of the spider which carries the planetary gears according to whether a heavy object is 60 to be moved or a relatively light one.

In the former case the rotation of the actuator 98 will cause its integral gear 96 to rotate the planetary gears 95, which by reason of their engagement with the internal gear 103 of the frame will cause the

revolution of the planetary gears about the central axis. By reason of the fact that the gear 95 which engages the gear 103 is of a different pitch from the gear 105 which engages the internal gear 106 of the drum, the 70 drum will be given a differential rotation relatively to that of the planetary system and great power will be transmitted from the actuator to the drum.

If an object of less weight is to be moved 75 the power may be applied through the hub 92 of the spider 93 which carries the planetary gears in which case the planetary gears will be directly rotated by the crank and a greater speed of revolution of the drum attained, the actuator 98 in the meantime rotating idly upon its axis.

In order to unreel the rope from the drum the locking pawl 116 will be removed from engagement with the ratchet teeth 115 85 whereupon the rope may be unwound rapidly, in such instance the planetary gears will of course revolve backwardly since there is no means provided in this embodiment of the invention for detachably connecting the drum from the internal gear through which it is driven by the planetary system.

In Figs. 9, 10 and 11 I have illustrated a modified form of my invention in which 95 a single planetary member is utilized to produce the required differential movement of the drum whereby a strong pull upon the rope may be exerted through very small and light mechanism.

As illustrated herein the frame preferably is in the form of two narrow straps 125—126, the ends of said straps being provided with inwardly extending abutting cylindrical posts 127—128 secured together by screws 129 or in any other suitable manner. These straps are provided with central apertures 130—131 adapted to receive the hubs of an actuator and a relatively rotatable member which will hereinafter be described. The 105 straps are so formed as to provide bearings 132—133 adapted to receive anti-friction rollers 134—135 to provide for the easy rotation of the actuator and said rotatable member. One of the straps 126 is provided 110 with an inwardly extending flange 136 provided with teeth 137 forming a rack adapted to be engaged by the planetary member.

The actuator desirably is in the form of a cylinder 138 having an eccentrically disposed stud 139 mounted in the bearing 130 and provided with an angular extension 140 to receive a suitable actuating crank.

The stud 139 is provided with a hollow inner end adapted to receive an extension 125 141 of the hub 150 of a rotatable member 151 in the form of a disk having an inwardly extending flange 152 provided with teeth 153 adapted to be engaged by the planetary member, the rotatable member 151 being de- 130

tachably secured to the drum 154 in a manner hereinafter to be described.

Roller or other antifriction bearings 155 desirably are interposed between the extension 141 of the rotatable member and the inclosing wall of the hub 139 of the actuator so as to provide for easy relative rotation of the actuator and rotatable member.

The planetary member is in the form of a cylindrical ring 156 held in proper endwise position by having near one end an inwardly projecting rib 157 lying within and engaging a peripheral rib 158 upon the inner end of the actuator, said planetary member being rotatably secured to the actuator by said ribs and by an annular cover plate 159 secured to the outer end of said actuator and engaging an annular recess in the end of said planetary member.

In order to reduce the friction between the actuator and the planetary member a series of anti-friction rollers 160 are interposed between the peripheral surface of the actuator and the inner surface of the planetary member.

The planetary member is provided with two sets of preferably integral teeth, one set 161 engaging the teeth 137 of the rack 136 while the other set 162 upon the opposite end engages the teeth 153 of the rotatable member. The teeth 161 and 162 are of different pitch so that a different number of teeth is provided in these respective gears. It therefore follows that the rotation and revolution of the planetary member through its actuator will impart a differential movement to the drum through the rotatable member 151.

The gear teeth of the respective members heretofore described may be of the usual form but preferably are slightly inclined as illustrated in Fig. 9 of the drawing in such a manner as to present greater resistance against breakage.

It being desirable, as heretofore stated, to provide for the independent rotation of the drum and its actuating member, means are provided for detachably securing the drum 154 to the rotatable member 151. A convenient means as illustrated in Fig. 11 comprises pawls 163 pivotally mounted upon screws or studs 164 carried upon the face of a rotatable member 151 and engaging recesses 165 formed in the inner face of one side of the drum 154.

In order to hold the pawls in engagement with said recesses each pawl may be provided with a tail 166 adapted to be engaged by a dog 167 mounted upon a stud or screw 168 on the face of the rotatable member as illustrated in Fig. 11. These dogs may be so constructed as to provide means for holding the pawl permanently in engagement with the recess of the drum or for withholding the pawls from such engagement.

In order to prevent the backward rotation of the drum during the reeling operation one or both of the flanges 169 of the drum may be provided with recesses 170 forming ratchet teeth adapted to be engaged by a pawl 171 mounted upon a pivot 172 projecting inwardly from the side frame or strap 126. This pawl may be held normally in engagement by a suitable spring in the manner heretofore described in connection with the embodiment of my invention illustrated in Figs. 1 to 6 inclusive. Suitable handles or yokes 173, 174 may be mounted upon the posts 127-128 in the manner aforesaid to provide means for attaching the anchoring rope.

In the operation of this embodiment of my invention a yoke 173 or 174 is attached to a stationary object. The hook upon the end of the rope which encircles the drum, as illustrated in Fig. 1 is attached to the object to be moved. Power is then applied through a crank to the extension 140 of the actuator hub, causing the rotation of the actuator and thereby effecting the rotation and revolution of the planetary member. By reason of the engagement of one set of teeth 161 of the planetary member with the teeth 137 of the stationary rack and the engagement of the teeth 162, which are of a different pitch from the teeth 161, with the teeth 153 of the rotatable member, which is secured to the drum, a relatively slow rotation will be imparted to the drum, with the application of multiplied power to the rope.

By disengaging the pawls 163 which are on the rotatable member from the recess 165 of the drum so that the latter is permitted to rotate independently of the drum, and withdrawing the pawls 171 from engagement with the flange of the drum, the rope may be unreeled by merely pulling upon the same.

While I have disclosed three embodiments of my invention herein it is to be understood that the invention is not limited to these particular structures but that it may be embodied in other forms and that various changes in the mechanism and construction may be made within the spirit and scope of the following claims. For example the central sun gear could be omitted and the planetary gears driven solely by an equivalent of the crank plate shown in Fig. 5 or the planetary system could be actuated by a shaft projecting from a planetary gear or the number of planetary gears can be varied.

A special advantage of my invention is its great compactness and great power in small compass of mechanism and with relatively small friction losses that are sustained with the mechanism arranged as described. The relative speed and power of the rope bearing drum and central actuator or crank can be varied within wide limits by modification of relative pitch of gears in the differential and

planetary system according to well known principles of mechanism.

Having thus described my invention what I claim as new and desire to secure by Letters Patent is;

1. A winch comprising a frame having a fixed gear, a winding drum rotatably mounted in said frame and having an internal gear, a crank disk having means adapted to be engaged by a crank, planetary gearing consisting of a plurality of composite gears journaled in said crank disk, each of said gears having members of different pitch engaging respectively said fixed gear and said internal gear, and a crank adapted to engage said crank disk to actuate said planetary system.
2. A winch comprising a frame having a pair of fixed annular gears, a winding drum having an internal gear mounted between said fixed gears, planetary gearing comprising composite members each having a pair of outer gears engaging said fixed gears and an inner gear of different pitch engaging said internal gear, a central actuator engaging the outer gears, and means for rotating said actuator.
3. A winch comprising a frame having a fixed annular gear, a drum rotatably mounted in said frame, an annular gear within said drum, planetary gearing within said annular gear comprising gears of different pitch in operative relation respectively to the annular gear of said drum and to said fixed gear, a central actuator within said planetary gearing, and alternative means for revolving said planetary gearing directly, or indirectly through said actuator, whereby differential movements having different speeds of rotation may be imparted to said drum.

4. A winch comprising a frame having a fixed annular gear, a winding drum rotatably mounted in said frame, an annular gear within said drum, planetary gearing within said drum comprising gears of different pitch located in operative relation respectively to the annular gear of said drum and to said fixed gear, a central actuator within said planetary gears, a crank disk rotatably mounted upon said actuator and having means engaging said planetary gears and forming spindles therefor, crank receiving means upon said crank disk and upon said actuator and a crank having means adapted to engage alternatively said actuator or said crank disk.

5. A winch comprising a drum, a planetary system within said drum, an actuator within said planetary system and a plurality of balanced, coöoperating anti-friction means carried respectively by said actuator and said planetary gearing adapted to reduce the friction between the relatively rotatable parts.

6. A winch comprising a frame, a drum rotatably mounted therein, an annular gear within said drum, planetary gearing within said annular gear and in operative relation thereto, means carried by the rotatable members of the planetary gearing adapted to provide a rolling contact between said members and frame, whereby the friction of the relatively rotating parts is reduced, and means independent of said rotatable members for actuating said planetary gearing.

7. A winch comprising a frame, a drum rotatably mounted therein and having an internal annular gear, a system of planetary gearing in operative relation to said drum and said frame and having a central actuator, and balanced antifriction means forming rigid parts respectively of said central actuator and said planetary gearing adapted to provide a rolling contact between said actuator, said planetary gearing and said frame whereby the friction between the relatively rotating members will be reduced.

8. A winch comprising a frame having fixed annular gears and annular bearing surfaces, a winding drum rotatably mounted within said frame having an internal gear and annular bearing surfaces, a system of planetary gearing mounted within said frame consisting of a plurality of composite gears having members of different pitch engaging respectively said fixed gears and said internal gear and provided with annular bearing surfaces engaging respectively with rolling contact the bearing surfaces on said frame and on said internal gear, and means for actuating said planetary system.

9. A winch comprising a frame having parallel fixed annular gears and annular bearing surfaces, a winding drum rotatably mounted within said frame having an internal gear and annular bearing surfaces, a system of planetary gearing mounted within said frame consisting of a plurality of composite gears having members of different pitch engaging respectively said fixed gears and said internal gear and provided with annular bearing surfaces engaging with rolling contact the bearing surfaces on said frame and on said internal gear, a central actuator gear engaging the members of one series of said composite gears and having bearing surfaces engaging those of said composite gears and means for rotating said actuator.

10. A winch comprising a frame having parallel fixed annular gears and annular bearing surfaces, a winding drum rotatably mounted within said frame having an internal gear and annular bearing surfaces, a system of planetary gearing mounted within said frame consisting of a plurality of composite gears having members of differ-

ent pitch engaging respectively said fixed gears and said internal gear, and provided with annular bearing surfaces engaging the bearing surfaces on said frame and on said 5 internal gear, a central actuator consisting of two gears adapted to engage the members of the series of composite gears which coöperate with the fixed gears on the frame, and having bearing surfaces engaging those 10 of said composite gears, means for detachably connecting one of said actuator gears to the other whereby the same may be removed to permit the assembling or dismounting of the apparatus, and means for 15 rotating said actuator.

11. A winch comprising a frame, a drum, means within said frame for actuating the drum and releasable means connecting said drum to its actuating means whereby said 20 drum may be permitted to rotate independently of said actuating means.

12. A winch comprising a frame having fixed annular gears, a drum rotatably mounted within said frame having an internal gear, a supporting spider rotatably mounted in said frame, a system of planetary gearing mounted within said frame consisting of a plurality of composite gears having members of different pitch engaging 25 respectively said fixed gears and said internal gear, said composite gears being provided with hubs having relatively loose connection with said spider, a central actuator operatively engaging said planetary 30 gears and means for rotating said actuator.

13. A winch comprising a frame, a drum rotatably mounted therein, an internal annular gear within said drum, an actuator, a rotatable member within said annular 40 gear engaging said actuator and said annular gear adapted to impart a differential movement to said annular gear and releasable means connecting said internal gear to said drum.

45 14. A winch comprising a frame, a drum

rotatably mounted therein, an annular gear within said drum having an external recess, a pawl on said drum adapted detachably to engage said recess, an actuator, a rotatable member within said annular gear 50 engaging said actuator and said annular gear adapted to impart a differential movement to the latter, and means for actuating said rotatable members.

15. A winch comprising a frame, a drum 55 rotatably mounted therein having annular apertured flanges, an annular internal gear within said drum having an external series of recesses, a pawl pivotally mounted in a recess in said drum adapted to engage a 60 recess in said gear and having an arm extending into an aperture in said flange, locking means for retaining said pawl alternatively in or out of engagement with a recess in said internal gear, a central actuator, 65 a rotatable member within said annular gear engaging said actuator and said annular gear adapted to impart a differential movement to the latter and means for actuating said rotatable member.

70 16. A winch comprising a frame having an annular fixed gear, a drum rotatably mounted therein, an internal annular gear having peripheral ratchet teeth, a pawl upon said drum adapted normally to engage said teeth, planetary gearing rotatably mounted within said annular gear and having gears of different pitch engaging respectively said fixed gear and said internal gear, an actuator engaging said planetary gearing and means adapted alternatively to rotate said planetary gear directly or through said actuator whereby different speeds of rotation may be imparted to said 75 drum or said drum released from its actuating mechanism to permit the rotation independently of said planetary gearing.

80 In testimony whereof, I have signed my name to this specification.

JOHN R. FREEMAN.
